UNITED STATES PATENT OFFICE.

FREDERICK S. KEELER, OF NEW YORK, N. Y.

GOLF-GAME APPARATUS.

Application filed April 29, 1921. Serial No. 465,384.

My invention relates to an indoor golf game and is more particularly intended to reproduce indoors the conditions of an actual outdoor golf game; that is to say, to afford a player difficulties to be overcome comparable to those encountered in a standard outdoor game, which difficulties are overcome in substantially the same manner, the skill of the player being rewarded and his errors being penalized in the same manner as in the outdoor game. To this end my invention includes playing implements which when used in combination with one another are adapted to produce the result sought. My invention also includes certain constructions of the various implements, such as the clubs, balls and "holes".

In order to achieve the results of my invention, it is essential that the various implements be of a character adapted for the extremely short distance encountered in an indoor game, but at the same time the implements must be so related as to reproduce upon a small scale the operation and effects of the corresponding implements in the standard game. For instance, the club intended for use in connection with my invention is of such a character that it would be totally inoperative with a standard ball and the ball is of such a character as to be totally inoperative with a standard club. In my invention the ball and club are so related that they are operative to produce the desired results in an indoor game.

In the drawings, I have shown—

In Figs. 1 and 2, a club designed for use in the game of my invention;

In Fig. 3, a modification of the club shown in Figs. 1 and 2;

In Figs. 4 and 5, a "hole"; and

In Fig. 6, a sectional view of a ball.

The club is preferably made from thin sheet metal cut in the form shown in Fig. 1, the blank comprising a playing face 1 and an extension 2 which is adapted to be wrapped around the shaft of the club 3 to hold it in place. The playing face of the club may be inclined to a greater or less extent from the vertical, so as to form clubs corresponding to the putter, mid-iron, mashie, etc. If desired, a sharp lower edge which might injure carpets may be avoided and the club may be given the effect of thickness on the bottom by bending over the blank in a direction approximately at parallel to the floor, as illustrated in Fig. 3.

The ball is preferably made of celluloid, or some similar material and may conveniently be made by forming two hemispheres 4 and 5 joined on the line 6. The surface of the ball may be either plain, or marked as in a standard golf ball, to obtain a greater grip upon the playing face of the club. The ball is so arranged that while it is of extremely light weight, all of the weight is concentrated near the surface, which enables the ball to respond to the greatest extent to the movement of the club.

With a ball and club so made and proportioned as to weight, I can obtain a very exact reproduction of the conditions of actual playing in a standard game. The ball will respond to a slice or pull of the club, may be given a back spin to drop dead, may be lofted, and when putted gives the player very much the same sensation as putting a standard golf ball with a standard club.

The game may be played upon a carpet to simulate the turf and pieces of furniture may be used to simulate bunkers or other obstacles upon or over which the ball may be played as in a standard game. The "holes" ordinarily used in an indoor golf game, comprising a shallow frustrum of a cone may be used, these "holes" being only of sufficient depth to hold the ball; that is to say, of a depth approximating the radius of the ball. In some "holes" I prefer to use a "hole" of my invention to simulate a tricky green; i. e., one in which the ball will roll away from the "hole" unless putted straight for it. Such a "hole" may comprise a hollow inverted dish formed of sheet metal, paste board, or other suitable material, such as illustrated in Figs. 4 and 5, in which the depth of the "hole" is considerably greater than the radius of the ball. The trickiness of the green may be varied by varying the depth of the "hole" or the declivity of its sides.

It will be evident that many modifications may be made without departing from the spirit of my invention and I therefore do not intend to be confined to the specific modification illustrated and described.

What I claim is:

1. A golf game intended for indoor use comprising a club having a head formed of sheet metal and a shaft, the head having integrally formed therewith an extension adapted to be wrapped about the shaft to secure the head thereto.

2. A golf game intended for indoor use

comprising a club having a head formed of sheet metal of a weight insufficient to propel a standard golf ball and a shaft, the head having an integrally formed sheet metal extension adapted to be conformed to the shape of the lower end of the shaft and to be wrapped about the shaft to secure the head thereto.

3. A golf club comprising a head formed of sheet metal and having one rounded protecting edge, and an element formed integral with said head and adapted to be wrapped whereby said element may form a socket.

4. A golf club formed of flexible sheet metal and comprising a head having a flanged lower edge, and an integrally formed extension adapted to be wrapped about the lower end of a shaft whereby a socket is formed to secure said head to a shaft.

5. A blank for a golf club head and socket comprising a single piece of sheet metal having a substantially rectangular forward portion and a rear portion angularly disposed with relation to said forward portion, said rear portion having one edge thereof formed in regular continuation of the lower edge of the above mentioned forward portion.

6. A blank for a golf club head and socket comprising a single piece of sheet metal having a substantially rectangular forward section and a rear section angularly disposed with relation thereto, a portion of said rear section overlapping a portion of said forward section whereby a sharply defined cut is provided, the rear section having one edge thereof formed in regular continuation of the lower edge of the above mentioned forward portion.

7. A blank for a golf club head and socket comprising a single piece of sheet metal having a forward portion of substantially

rectangular shape, and a rear portion angularly disposed with relation to said forward portion.

8. In a golf club, means for securing the head thereof to the shaft, comprising a flexible sheet metal element formed as an extension of the head and adapted to be angularly wrapped about the shaft.

9. An indoor golf game apparatus comprising a light, hollow ball, a plurality of hollow frusto-conical holes of greater depth than the diameter of said ball and adapted to receive said ball, and a golf club, the weights of said golf club and said ball being substantially and proportionately below the weights of standard units and their dimensions substantially equal to standard units.

10. An indoor golf game apparatus comprising a light, hollow ball, a plurality of hollow frusto-conical holes of greater depth than the diameter of said ball, said holes being adapted to be in various places in a room or the like to simulate a golf course and to receive said ball, and a club provided with a sheet metal head for propelling said ball, the weights of said golf club and said ball being substantially and proportionately below the weights of standard units and their dimensions substantially equal to standard units.

11. An indoor golf game apparatus comprising a relatively light ball capable of flight, a club for propelling said ball and a plurality of hollow frusto-conical holes adapted to receive said ball, the weights of said golf club and said ball being substantially and proportionately below the weights of standard units and their dimensions substantially equal to standard units.

In testimony whereof, I have signed my name to this specification this 26th day of April, 1921.

FREDERICK S. KEELER.
